Application May 5, 1937, Serial No. 140,845

6 Claims. (Cl. 88—14)

This invention relates to testing apparatus, and more particularly to apparatus for testing the headlights of motor vehicles.

In the construction of lighting equipment for 5 automotive vehicles, it is common practice to employ an electric bulb or lamp to supply a source of light. A reflector is customarily positioned behind the lamp to reflect the light rays emanated from the lamp, and to transmit them 10 from the mouth of the reflector in generally parallel lines or shafts somewhat in the form of a cylinder.

If the light source is behind a focal point of 15 the reflector the light rays diverge thereby producing a blind spot, or sector of low light intensity at the central portion of the shaft of light transmitted. If the light source is ahead of the focal point of the reflector, the rays of light converge and cross thereby producing the blind 20 spot or point of low light intensity in the central portion of the shaft of light transmitted from the headlight. Various expedients have been resorted to in an effort to overcome the difficulties thus 25 encountered such for example as the various focusing devices utilized by certain manufacturers, whereby the lamp may be moved longitudinally with reference to the reflector until the focal point, or point of greatest light intensity is reached.

30 The cylindrical shaft of light thus transmitted by the reflector is generally too concentrated and narrow to properly illuminate the highway, and has the further disadvantage that it blinds or impedes the vision of the occupants of vehicles 35 travelling in the opposite direction on the highway. In an effort to avoid these disadvantages, and also to protect the reflector, a lens is customarily employed to bend the rays of light in such a manner as to produce more uniform lighting 40 of the highway, and to confine the principal portion of the light rays below a horizontal plane parallel to the surface of the road. Many different forms of lenses having various combinations of prisms or flutes may be employed to diffuse the light vertically and horizontally in a desired manner.

In view of the importance of having proper and adequate lighting equipment on vehicles considerable attention has recently been directed 50 to this phase of vehicle operation. A number of states have enacted laws governing the operation of the lighting equipment of vehicles, in an effort to avoid the hazards encountered in the operation of faulty headlighting equipment.

55 It is particularly important that the headlights

be aimed in a direction to light the highway for a sufficient distance in front of the vehicle to permit the operator to see objects in sufficient time to stop the vehicle, from any speed at which the vehicle may be running, before it reaches the object. It is therefore desirable that the headlights be positioned in such a manner as to direct the light as far down the road as possible, consistent with the necessity that the lights be sufficiently low as not to shine in the 10 eyes of occupants of vehicles travelling in the opposite direction on the highway.

A loading allowance, defined as the angular deflection of the headlights due to the loading 15 of the rear portion of the vehicle must also be taken into consideration in connection with headlight design and maintenance.

In view of the fact that the lighting equipment 20 of vehicles is normally subjected to rather severe operating conditions which tend to alter the adjustment thereof to misdirect the light emanating therefrom, it is desirable that means be provided to quickly check the headlighting equipment of vehicles to determine whether they 25 are in satisfactory operating condition.

An object of this invention is therefore to provide 30 means for checking the lighting equipment of motor vehicles to determine whether it is in proper operating condition.

A further object of the invention is to provide 35 means for determining the direction of the light rays emanating from the headlight.

Another object of the invention is to provide 40 a light sensitive cell to indicate the intensity of the light transmitted from a headlight.

Yet a further object of the invention is to provide 45 a headlight tester, which may be operated rapidly to determine whether or not the headlighting equipment falls within predetermined approveable limits.

Yet a still further object is to provide means 50 whereby a light sensitive cell may be accurately aligned with the headlight to indicate the point of maximum light intensity transmitted from the headlight.

Another object is to provide means including 55 scales to accurately determine the direction of the shaft of light of greatest intensity emanating from the headlight.

A still further object is to provide manually 60 operable adjusting means to accurately align the headlight tester with the direction of travel of the vehicle.

A further object is to provide means including 65 a condensing lens and a screen to determine the

general relation of the light beam pattern transmitted from a headlight.

Yet a still further object of the invention is to provide visual means for checking the intensity of a confined shaft of light emanating from a headlight.

Another object is to provide an electrically actuated meter operably connected to a light sensitive cell adapted to receive a restricted amount of light from a headlight to indicate the intensity of the light transmitted.

A further object is to provide a counterbalanced casing enclosing a restricted tube wherein a plurality of manually operable devices are provided to accurately align the tube with the point of greatest light intensity transmitted from the headlight.

Other objects and advantages of this invention will be apparent from the following detailed description, considered in connection with the accompanying drawings submitted for purposes of illustration only and not intended to define the scope of the invention, reference being had for that purpose to the subjoined claims.

In the drawings, wherein similar reference characters refer to similar parts throughout the several views:

Figure 1 is a side elevation, partly in section, of a headlight tester embodying the present invention;

Figure 2 is an end elevation, partly in section, of the device illustrated in Figure 1, as viewed from the righthand side thereof;

Figure 3 is a plan view of the device illustrated in Figure 1;

Figure 4 is a view illustrating the fixed and movable scales;

Figure 5 is a side sectional elevation of the mechanism illustrated in Figure 6;

Figure 6 is a view taken substantially on the line 6—6 of Figure 5;

Figure 7 is an end elevation, partly in section, of a portion of Figure 1;

Figure 8 is a plan view, partly in section, of a portion of Figure 1;

Figure 9 is a side elevation, partly in section, of a portion of Figure 1;

Figure 10 is a view taken substantially on the line 10—10 of Figure 9;

Figure 11 is a view, partly in section, taken substantially on the line 11—11 of Figure 2;

Figure 12 is a sectional view taken on the line 12—12 of Figure 1;

Figure 13 is a sectional view taken on the line 13—13 of Figure 5; and

Figure 14 is a fragmentary bottom view of a portion of Figure 13.

Referring more particularly to Figures 1 and 2 there is shown for purposes of illustrating this invention, a headlight tester positioned in operative relation with reference to a headlight 10 of a motor vehicle 12. A generally rectangular shaped box 14 is positioned between a pair of standards or columns 16. The standards 16 are fixed with reference to a base 18 having rollers 20 and 22. The rollers 20 are adapted to roll in a track 24, to move the light tester laterally with reference to the vehicle 12.

The box 14 is supported by cables 26 connected to counterweights 28 slidable in the standards 16. The cables 26 pass over pulleys 30 positioned at the top of the standards 16, and pass around a vertical carriage 32. The counterweights 28 balance the weight of the box 14 and the vertical carriage 32. The vertical carriage

32 is provided with spaced rollers 34 adapted to be received in tracks 36 fixed to the standards 16, as more clearly shown in Figure 12, to facilitate moving the carriage vertically. Handwheels 38 connected to the pulleys 30 are provided to raise and lower the vertical carriage 32 and the box 14. The box 14 and the carriage 32 may also be raised or lowered by merely applying pressure thereto in the direction in which it is desired to move them.

The box 14 is slidably mounted laterally with reference to the vertical carriage 32 on anti-friction members 38 interposed between rails 40 carried by the vertical carriage 32, and rails 42 carried by brackets 44 operably connected to a member 46 supporting the box 14. The box 14 may be moved laterally by means of a handwheel 48 operably connected to a pinion 50 positioned to mesh with a geared rack 52 supported by a bracket 54 fixed to the brackets 44.

The box 14 is supported on a leveling plate 56 having a spherical member 58 fixed thereto. The member 46 is provided with a spherical indentation 60 adapted to receive the spherical member 58. A pin 62 projects through the spherical member 58, and is limited to vertical movement by means of a bifurcated guide 64 fixed to the member 46.

The box 14 may be tilted longitudinally about the spherical members 58 and 60 by means of a leveling screw 66. Movement of the leveling screw 66 compresses or permits expansion of a spring 68 interposed between the leveling plate 56 and the member 46, the pin 62 moving in the guide 64.

The box 14 may be tilted laterally about the spherical members 58 and 60 by means of a leveling screw 70. Movement of the leveling screw 70 compresses or permits expansion of a spring 72 interposed between the leveling plate 56 and the member 46, the pin 62 rotating about its own axis in the guide 64.

The spherical member 58 is restrained against upward movement with reference to the spherical indentation 60 by means of a stud 74 passing through an enlarged aperture in the member 60, and a spring 76 which yieldingly urges spherical washers 78 and 80 into engagement with the spherical members 58 and 60.

An oscillating plate 82 is pivotally mounted on a bolt 84 to turn on the leveling plate 56. A bracket 86 fixed to the leveling plate 56 engages a nut 88. A screw 90 fixed longitudinally in bearings 92 carried by the oscillating plate 82 engages the nut 88 to move the box 14 with reference to the leveling plate 56 upon actuation of thumb screws 94 fixed to the screw 90.

A graduated sector 96 fixed to the developing plate 56 cooperates with a movable zero reference member 98 carried by a sector 100 fixed to the oscillating plate 82, to indicate the angular deflection of the box 14 with reference to the leveling plate 56.

Means are provided to move the box 14 longitudinally with reference to the member 46. A track 102 fixed to the oscillating plate 82 cooperates with another track 104 carried by the box 14 to confine therebetween a plurality of balls 106 separated by spacers 108 to permit the box 14 to be moved longitudinally with reference to the vertical carriage 32.

A light sensitive cell 110 is positioned on a bracket 112 in the box 14. Area restricting means, such, for example, as a tube 114 is universally mounted at one end in the forward por-

tion of the box 14. The other end of the tube 114 is fixed to the bracket 112.

Means are provided to move the rear end of the tube 114 and the cell 110 laterally and vertically in the box 14.

The cell 110 and the bracket 112 are, as disclosed in Figure 13, pivotally connected to laterally movable U-shaped member 116 received between laterally disposed guides 118 and 120 slidably supported on spindles 122. This connection includes U-shaped clips 123 and 123' connected by a pin 123''. As disclosed in Figure 13, the clips are pivotally connected to the bracket 112 and to the upper portion of U-shaped member 116, the latter at its base portion being slotted, as disclosed in Figure 14, to receive a pin 124' extending from the end of the bracket 112. Auxiliary spindles 124 cooperate with the spindles 122 to support the upper and lower plates 126 and 128 respectively.

The cell 110 and the end of the tube 114 may be moved vertically by means of the elevating screw 130 passing through a threaded member 132 carried by the guide 120. The elevating screw 130 is provided with a knob 134 projecting through the top of the box 14.

The cell 110 and the end of the tube 114 may be moved laterally in the box 14 by means of a splined driving shaft 136 having a knob 138 fixed thereto. A sprocket 140 slidably mounted on the shaft 136 and rotatably mounted in the guides 118 and 120, drives a chain 142. The chain 142 passes over laterally spaced sprockets rotatably mounted on studs 144 interposed between the guides 118 and 120. The chain 142 is connected to the laterally movable member 116 to move the cell 110 and the end of the tube 114 laterally between the guides 118 and 120.

A level 146 carried by the plate 126 is provided to indicate when the guides 118 and 120 are level.

A meter 148 having a dial 150 and a pointer 152 is provided to indicate the intensity of the light to which the cell 110 is subjected. The meter 148 is oscillatably mounted on the box 14 so that it may be turned so that it may be observed from various angles.

A scale support 160 including spaced glasses 162 is mounted on the plate 126. A pair of fixed upstanding scales 164 disposed back to back are mounted transversely on the plate 126 between the spaced glasses 162. The scales 164 are provided with horizontally extending zero reference lines 166, and laterally spaced graduations 168 extending laterally in both directions from a central zero reference mark 170 to measure the lateral deviation of the light beam in inches at twenty-five feet, which is of course equivalent to feet of deviation at a distance of three hundred feet. The scales 164 are also provided with laterally spaced graduations 172 to measure degrees of light beam deviation.

A pair of movable scales 174 carried by the laterally movable member 116 project through laterally extending apertures in the plate 126 and are movable laterally and vertically between the fixed scales 164 and the spaced glasses 162 by means of the knobs 134 and 138.

The vertical scales 174 are provided with vertically extending zero reference lines 176, and vertically spaced indication marks 178 to measure the vertical deflection of the light beam in inches at twenty-five feet. The scales 174 are also provided with vertically spaced graduations 180 to measure degrees of vertical light beam deviation.

A viewing screen 200 may be mounted on the

box 14. The screen 200 is preferably carried by a standard 202 pivotally mounted at 204 so that the screen and standard may be turned to an inoperative position as illustrated, when not in use.

It has been found from experiments with various types of headlights that a so-called standard pattern may be produced for any type of headlight. A card marked to indicate the proper light pattern for the particular headlight being tested may be mounted on the standard 202, pivotally mounted at 204. The card may be elevated with reference to the screen 200 for purposes of comparison between the standard light pattern and the light pattern actually produced by any given headlight. If the pattern of the light being tested does not conform to the standard pattern for that type of light, suitable corrections may be made to correct the light.

If desired a condensing lens 210 may be pivotally mounted at 212 on the box 14 to condense the light pattern, formed by the light being tested, on the screen 200 for purposes of comparison.

A forward sight 220 and a rear sight 222 carried at the top of the scale support 160 may be employed to align the box 14 with the central line of the vehicle 12, the lights of which are being subjected to test. A marker 226 carried by the forward sight 220 may be employed to accurately align the screen 200 or the condensing lens 210 with the central portion of the light being tested.

The operation of this light tester is as follows. The car 12, the lights of which are to be tested is positioned in such a manner that the lights thereof will be as nearly parallel as possible, and adjacent, with the track 24. The light tester is then rolled on the track 24 in front of the vehicle. The box 14 is then accurately aligned with the central portion of the vehicle 12 by lining up the sights 220 and 222 with the central portion of the vehicle. The box 14 may be turned angularly by means of the thumb screws 94 to oscillate the box 14 with reference to the member 46 to accurately align the device with the central portion of the vehicle. The light tester is then moved on the track 24 until the forward end of the box 14 is positioned directly in front of one of the headlights 10 to be tested. The thumb screws 66 and 70 may then be actuated to oscillate the box 14 longitudinally and laterally to level the plate 126. The level 146 may of course be observed to indicate when the plate is level.

The handwheel 48 may then be actuated to move the box 14 with reference to the vertical carriage 32 to accurately align the forward end of the box 14 with reference to the desired portion of the light 10.

The light is then turned on, whereupon the light sensitive cell 110 will be subjected to the restricted quantity of light passing through the tube 114 when the tube 114 and cell 110 are in the path of the light beam. The pointer 152 of the meter 148 moves over the dial 150 to indicate the intensity of the light to which the cell 110 is subjected.

The knobs 134 and 138 may then be actuated to move the rear end of the tube 114 and the cell 110 vertically and laterally in the box 14 to locate the angular direction of the light rays of greatest intensity emanating from the headlight 10. When the meter 148 indicates that the point of maximum light intensity has been reached, the relation between the movable scale 174 and the fixed scale 164 may be observed to indicate the direction of the maximum light intensity emanating from the headlight.

- The graduations 178 of the movable scale 174 may be read against the zero reference line 166 of the fixed scale 164 to indicate inches of vertical light beam deviation at a distance of twenty-five feet, or feet of light beam deviation at a distance of three hundred feet. The zero reference line 176 of the movable scale 174 may then be read against the graduations 168 of the fixed scale 164 to indicate inches of light beam deviation laterally at a distance of twenty-five feet or feet of lateral light beam deviation at a distance of three hundred feet, left or right depending on where the zero reference line 176 of the movable scale lies with reference to the zero reference character of the scale 168. It will be apparent that the graduations 180 of the movable scale 174 may be read with the graduations 172 of the fixed scale 164 to indicate vertical and lateral light beam deviation in degrees.
- It will of course be apparent that the meter 148 may be turned so that it may be read from any desired angle to facilitate making suitable corrections of the headlight 10 to correct the light emanating characteristics of the light to conform to predetermined requirements. The vertical and movable scales 174 and 164 respectively being double faced may be observed from either side.
- If desired a door 184 may be opened by means of the knob 186 to observe the light sensitive cell 110 while the test is in progress.
- After one headlight has been tested the box 14 may be moved longitudinally with reference to the columns 16, and the device rolled laterally to align the box with the other light to be tested. The box 14 may then be moved longitudinally into operative position with reference to the other light to be tested, and the testing of that light effected in the same manner as indicated above.
- It will be observed that the movable zero reference member 98 carried by the sector 100 may be positioned adjacent the zero reference character of the sector 96 to indicate the proper aligned position of the box 14 with reference to the headlights. It is therefore unnecessary to align the box angularly to test the second light in the event that the vehicle has not been moved.
- After the direction of the light transmitted from the headlights has been determined the reading of the meter 148 will of course be observed to determine whether or not the intensity of the light falls within predetermined limits.
- It will be understood that this invention is not to be limited to testing vehicle headlights as it may be employed to test any light emanating member, or the principle may also be applied to remote indicators for various types of equipment such, for example, as service equipment such as brake testers, wheel aligners, dynamometers, etc., wherein the light from a light source of varying intensity, controlled by a movable element of the service apparatus to indicate the efficiency of the member being tested, is directed to a light sensitive cell operably connected to a meter, employed to indicate whether the member being subjected to test falls within desirable predetermined limits.
- While the invention has been described with particular reference to a limited number of desirable embodiments, it is to be understood that various changes may be made in the arrangement of parts and the details of construction of the moving and indicating mechanisms without departing from the spirit of the invention as defined by the following claims.

I claim:

1. A device for testing vehicle headlights comprising a base, a pair of spaced columns on the base, a box mounted between the columns, means to move the box laterally, vertically and longitudinally with reference to the columns, an aperture in the forward end of said box, a tube within the box universally pivotally connected at one end to said box adjacent said aperture, a light sensitive cell connected to said tube at its other end so as to receive light passing through the tube, means to move said tube and cell about said pivotal connection, means to indicate the intensity of light to which the cell is subjected, and means actuated by the movement of the tube to indicate the position of said tube with reference to a predetermined normal position of the tube.

2. A device for testing vehicle headlights comprising a track, a base having rollers adapted to engage the track, supporting means carried by the base, a box carried by the supporting means, a level on the box, manually operable means to level the box longitudinally and transversely, manually operable means to move the box angularly in an approximately horizontal plane with reference to the supporting means, a tube within the box universally pivotally connected at its one end to the forward end of said box, an aperture in the box adjacent said universal connection, a light sensitive cell rigidly attached to said tube adjacent its other end and positioned to receive light transmitted through the tube, manually operable means to move the box vertically, laterally, and longitudinally with reference to the supporting means, manually operable means to move said tube and the light sensitive cell about the pivotal connection, means to indicate the intensity of the light to which the cell is subjected, and means actuated by the movement of the tube to indicate the position of said tube with reference to a predetermined normal position of the tube.

3. In a testing device for vehicle headlights, a support, means mounted on said support and provided with an aperture for selecting and restricting an area of a headlight, elongated light transmitting means for confining and transmitting light emanating from said selected and restricted area of the headlight as determined by said aperture, means for mounting said light transmitting means on the support for universal pivotal movement thereof about a point immediately adjacent said aperture, a light sensitive cell positioned to receive at all times the light transmitted through said light transmitting means, light intensity indicating means connected to said cell, means for moving said light transmitting means universally pivotally about said point immediately adjacent said aperture to determine the position at which maximum light intensity derived from the selected area and passing through said aperture obtains at said cell, and means actuated by movement of said light transmitting means to indicate the extent of displacement of the light transmitting means from a predetermined reference position.

4. A device for testing vehicle headlights comprising a base, supporting means carried by the base, a box carried by the supporting means, means to move the box laterally, longitudinally, and vertically with reference to the supporting means, counterbalancing means associated with the supporting means to facilitate vertical movement of the box, a level on the box, means associated with the supporting means to level the box longitudinally and transversely, a tubular light-transmitting member within the box and having its one end adapted to receive the light

- emanating from a selected and restricted area of the headlight, universal mounting means for said tubular member in the forward end of said box, a light sensitive cell within the box, means for maintaining said cell in light exchange relationship at all times with the other end of said tubular member, means to move the tubular member universally pivotally in said mounting means to locate the position of the tube at which greatest light intensity obtains at said cell, and means actuated by movement of the tubular member to indicate the position of the tubular member relative to a predetermined line through the selected area.
15. 5. A device for testing vehicle headlights comprising a base, a pair of spaced columns on the base, a box mounted between the columns, adjustable means to level the box longitudinally and transversely, a tube within the box universally pivotally mounted on the forward end of the box adjacent one end of said tube, an aperture in the end of the box adjacent said pivotal connection, a light sensitive cell within the box, means for maintaining said cell at all times in light exchange relationship with the other end of the tube to receive light transmitted through said tube, means to indicate the intensity of light to which the cell is subjected, means to move the

box laterally, vertically, and longitudinally with reference to the columns to bring the first named end of the tube into juxtaposition with a selected and restricted area of the headlight, means to move said tube about said pivotal connection, and means actuated by movement of said tube to indicate the position of the tube with reference to a predetermined line through the selected area.

6. A device for testing vehicle headlights comprising a box, a tube within the box universally pivotally connected to the forward end of the box adjacent one end of the tube, a light sensitive cell within the box, means for maintaining said cell at all times in light exchange relationship with the other end of said tube thereby to receive light transmitted through the tube, means to indicate the intensity of the light received by said cell, means to move said tube about said pivotal connection, and means for indicating the displacement of the tube from a predetermined reference position relative to the box comprising a scale carried by the box, a second scale carried by the tube, said second scale being positioned in cooperative relationship at all times with the first scale, said scales having their graduations extending at right angles to each other.

LEE L. SMALLEY.
